US00D799600S

(12) **United States Design Patent** (10) **Patent No.:** **US D799,600 S**
Chatterjee et al. (45) **Date of Patent:** ** *Oct. 10, 2017

(54) **CONTROLLER**

(71) Applicant: **Microsoft Corporation**, Redmond, WA (US)

(72) Inventors: **Monique Chatterjee**, Seattle, WA (US); **Richard T. Hanks**, Seattle, WA (US); **William Bennett Mabry**, Seattle, WA (US); **Austin Porter**, Seattle, WA (US)

(73) Assignee: **Microsoft Corporation**, Redmond, WA (US)

(*) Notice: This patent is subject to a terminal disclaimer.

(**) Term: **15 Years**

(21) Appl. No.: **29/578,414**

(22) Filed: **Sep. 21, 2016**

Related U.S. Application Data

(63) Continuation of application No. 29/571,165, filed on Jul. 14, 2016.

CLAIM

The ornamental design for a controller, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front perspective view of a controller showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken line showing of the remainder of the controller in FIGS. 1–7 is for environmental purposes only and forms no part of the claimed design.

1 Claim, 7 Drawing Sheets
(7 of 7 Drawing Sheet(s) Filed in Color)
